ROTARY DRILLING MACHINE

William J. Mitchell, San Francisco, Calif., assignor to Pneumatic Tool Company, New York, N. Y., a corporation of New Jersey

Application May 31, 1933, Serial No. 673,728

5 Claims. (Cl. 255—51)

My present invention relates to an improved rotary drilling machine of the high speed, diamond, rock drill type, which, while herein illustrated as a horizontal drilling or boring machine, is also adapted for vertical operations. When employed for tunneling or mining operations the machine is usually mounted upon an upright column, or upon a horizontal arm of the column, and the machine may be adjusted to 10 various angles for drilling or boring holes in earth, the power unit which forms a part of the machine, being also adjustable with the machine.

In the exemplified structure of the drawings I employ a tubular, sectional, drill rod having a 15 supply of water thereto, and at the end of the drill rod a rotary, diamond bit is mounted. Means are employed for quickly disconnecting the driving connections in order that an additional tube section may be used on the drill rod, and 20 the power unit is mounted directly on the drill rod for high speed in drilling and for compactness and simplicity in the arrangement of the parts of the machine.

The feed mechanism is of the screw operated 25 type and manually controlled, and a spring mechanism is combined with the feed mechanism to impose pressure on the bit at all times, together with means for regulating the pressure.

While the machine is well adapted for various 30 boring or drilling purposes, it is especially useful in drilling holes in hard rock for blasting purposes, and as distinguished from the "hammer" type of drills usually employed for blasting, the drill of my invention reaches a substantially 35 higher speed, and at the same time eliminates the objectionable dust that arises from the operation of the drills now in use and with which I am familiar.

The invention consists in certain novel combinations and arrangements of parts as will hereinafter be more fully set forth and claimed. In 40 the accompanying drawings I have illustrated one complete example of the physical embodiment of my invention wherein the parts are combined and arranged according to the best mode I have 45 thus far devised for the practical application of the principles of my invention, but it will be understood that various changes and alterations may be made in the exemplified structure, within 50 the scope of my claims, without departing from the principles of my invention.

Figure 1 is a view in side elevation at the rear end of the machine embodying my invention.

Figure 2 is a horizontal sectional view, as at 55 line 2—2 of Figure 1.

Figure 3 is an enlarged view showing one of the bearings in section for the drill, together with the self centering drive chuck which couples the tubular drive shaft with the tubular drill rod.

Figure 4 is a view showing the driving unit with 5 the thrust bearings of the motor in section.

Figure 5 is a longitudinal, vertical sectional view showing the screw-feed and the tension means combined therewith.

Figure 6 is a transverse sectional view at line 10 6—6 of Figure 5, looking toward the front of the machine; and Figure 7 is a similar view at line 7—7 of Figure 5 looking toward the rear of the machine.

Figure 8 is a vertical sectional view, enlarged, 15 of the front or driving chuck, in locked position, which couples the motor-spindle or tubular drive shaft to the tubular drill rod.

Figure 9 is an inner face view of the head of 20 the chuck showing the pivoted cam-jaws unlocked and loosely engaging the drill rod.

Figure 10 is a sectional view of the rear self-centering chuck.

Figure 11 is a face view of the rear chuck as 25 seen from the right in Figure 10.

In the preferred form of the invention as illustrated in the drawings I employ a rotary diamond bit 1 illustrated in Figure 1, which is preferably hollow and provided with one or more water holes 2. The bit is coupled at the front 30 end of the front tubular section 3 of the tubular drill rod, which as shown is made up of sections that may vary in length from three feet to twenty feet, and these sections are added at the rear to the drill rod as the boring proceeds. A water 35 connection 4 in Figure 1 is provided for the drill rod and water is supplied to the bit through the tubular drill rod, from the hose 5 to facilitate the operation of the bit, eliminate dust from the drilling machine, and to carry off the débris or 40 cutting of the bit, through the bored hole.

For rotating the drill rod and bit I employ a 45 rotary electric motor 6, or other suitable rotary motor may be employed for this purpose that is adapted for directly driving the drill rod. In the exemplified structure of Figure 1 I have shown a one horse power motor of the single phase type, operating at approximately 1800 revolutions per minute, and of course connected with a suitable electric supply.

The rotor 1 of the motor in Figure 5 is fixed 50 with a pressed fit on the tubular drive shaft which has an interior diameter sufficient to neatly enclose the drill rod sections, and the drive shaft is fashioned with an enlarged portion, within the 55

- rotor, that forms end shoulders 9, 9 on the shaft. The shaft and rotor are mounted to revolve in the motor 7 and ball bearings 10, 10 are provided in the motor casing for the drive shaft.
- 5 In Figure 5 it will be seen that the bearings are located against the spaced annular shoulders 9, 9, of the shaft, and the bearings thus form thrust bearings in combination with the annular shoulders 9, 9, to take up the pressure of the feed mechanism on the drill rod and the drive shaft.
- 10 An additional bearing for the drive shaft is provided forward of the motor, which bearing is supported from the drill frame 11 by a bracket 12, and the bearing head 13 has enclosed therein ball bearings 14. The bearing is of the aligning type and is provided with a retaining end plate 15 bolted to the hollow, circular head 13, and this bearing, as indicated in Figure 1 is spaced from the motor a sufficient distance to insure a stable operation of the rotary drive shaft which passes through the bearing, as best seen in Figure 3.
- 15 The drive shaft is coupled to the enclosed drill rod by means of a self-centering chuck, located in front of the bearing 13, rigidly mounted on the end of the shaft, and frictionally engaged with the exterior periphery of the drill rod within the shaft. As seen in Figure 8 the chuck or coupling includes a drive head 16, into which the end of the drive shaft is securely threaded, and an enclosing sleeve or shell 17 threaded on the head. Mounted on the inner face of the head within the shell for frictional engagement with the periphery of the drill rod are a number of friction jaws 18 that are caused to grasp the drill rod when the shell is turned, and the latter is provided with a tapered or cone-face ring 19 that rides down the edges 20 of the jaws, forcing the jaws into frictional engagement with the drill rod, thereby transmitting the rotary motion of the drive shaft to the enclosed drill rod and to the bit 1 for the drilling or boring operation. The jaws 18 each have a cam face 21, and by means of trunnions 20' the jaws are pivoted in sockets in the head and also in complementary sockets of the removable head-plate 16'. A tension spring 18' engages each jaw, and the springs are anchored to the face of the head on pins 17'. The springs, it will be understood, tend to rock the jaws on their trunnions to released position.
- 25 The cone-ring or wedge-ring 19 is limited in its movement by a split resilient ring 19' seated in an interior annular groove of the sleeve, and the head plate 16' is fastened to the head in any suitable manner as by bolts 16a in Figure 9. At the rear end of the motor-spindle or tubular shaft 8 a centering chuck also rigidly joins the spindle with the drill to center the rod. This chuck, as seen in Figures 10 and 11, includes a tightening sleeve 8' that is threaded on the externally threaded collar 8a which is mounted on the end of the drive shaft and attached thereto by screws or bolts 8b. A split, resilient, tapered clamp ring 8c encircles the drill rod within the sleeve 8' and abuts against the end of the drive shaft. By means of an inner cone-face 8d on the sleeve 8' the split ring is centered and clamped on the drill rod to couple the latter with the shaft 8.
- 30 The drill frame, motor and drive shaft are reciprocable with the drill rod, and these parts are advanced as the boring or drilling proceeds, the drill frame sliding on a base frame or saddle 22 which is of ample length, and open at its under side. To facilitate the sliding movement of the

drill frame, the base frame is fashioned with dove-tail grooves 23, and the drill frame is fashioned with complementary dove-tail tongues 24 that co-act in guiding the movement of the drill frame and retain these parts in their proper relative positions.

35 The upper flat wall of the base-frame is provided with a pair of spaced, central, longitudinally extending slots as 25 designating a wide front slot, and 26 designating a narrow, rear slot, 10 to accommodate the feed mechanism.

40 The entire mechanism is usually mounted on the upright column or upon a horizontal arm of the upright column, generally employed in mining operations, and for this purpose I provide a trunnion 27 that is bolted to the base-frame by means of the attaching plate 28 located at the under side of the base-frame or saddle 22, and the machine may be adjusted at various angles for drilling or boring.

45 By the use of manually operated feed mechanism the parts supported on the slideable drill frame 11 are advanced with the drill frame to the work, and by reverse movement of the feed mechanism these parts are retracted. The feed mechanism operates in connection with a pressure plate 29 that is rigidly attached to the drill frame, by means of the angle bracket 30 which is bolted at 31 to the drill frame.

50 The angle bracket projects up through the front slot 25 of the base frame and this slot permits the relative movement of the pressure plate within the hollow base frame. On its rear face the pressure plate is fashioned with an annular flange 32 forming a circular cup which is concentric 35 with a central bolt hole or screw hole in the plate, and at its sides the plate is fashioned with a pair of lateral, perforated ears or lugs 33.

55 The feed screw 34 extends loosely through the center hole of the pressure plate, and at its rear end the screw is journaled in bearings 35 provided in the rear end wall of the base frame, the usual retaining collars 35' being provided to prevent longitudinal movement of the screw as the latter is manually turned through the use of a hand wheel 36 mounted on the end of the screw at the rear of the machine.

60 A non-rotating, but travelling nut 37 is mounted on the screw between its bearing and the pressure plate, and this nut has an integral guide lug 38 50 projecting upwardly from the nut and adapted to reciprocate in the guide slot 26 of the base frame. As indicated in Figure 6, the guide lug is guided by the side walls of the slot 25, and the nut, integral with the lug is thus prevented from turning on the screw, but is caused to travel toward and from the pressure plate that is fixed on the drill frame, and the range of movement of the traveling nut with relation to the base frame is limited by the length of the slot 26 that may 60 correspond with the feed of a drill-rod section.

65 The traveling nut is also fashioned with an annular flange 39 at its front side, forming a cup complementary to and opposed to the cup 32 on the pressure plate, and a tension spring 40 is coiled about the screw and interposed between these two cups for the purpose of at all times imposing a pressure on the rotary bit 1.

70 At its sides, the traveling nut is fashioned with a pair of lateral, perforated lugs 41 complementary to the lugs 33 of the pressure plate, and two adjustment bolts or tie bolts 42, 42, join these pairs of lugs, one at each side of the screw and spring. The long bolts have heads 43 against the exterior faces of the lugs 41 of the nut, and 75

the threaded ends of these bolts which pass loosely through the lugs 33 of the pressure plate are provided with nuts 44 at the exterior sides of these lugs 33. By turning the nuts on the threaded ends of the bolts the pressure plate, and the parts to which it is attached, are pushed toward the nut, thereby providing an initial compression of the spring 40 between its two cups 32 and 39. During this compression movement, the pressure plate is moved to the right in Figure 2 along the bolts 42, 42, and the screw 34. Thus an initial tension or resiliency is provided for the drilling machine, before the boring or drilling operation starts, and this tension is exerted through the pressure plate and drill frame, the motor and the driving shaft, to the drill rod, and so to the drill bit on the working end of the rod. This tension is exerted on the drilling rod and bit at all times during the drilling operation, to automatically maintain the bit in operative position.

By the use of the hand wheel, an additional compression is imparted to the spring, as the screw is turned and the nut caused to travel to the left in Figure 2. Thus a resilient pressure is initially imposed on the bit, and thereafter a resilient feed is controlled by the use of the hand-wheel, the latter being gradually turned as the drilling proceeds to maintain the tension of the spring and the pressure on the pressure plate and drill frame to which it is attached.

After the drill has been advanced or fed the full length of the slot 26 in the base frame, say eighteen inches, or more, the drill is retracted, after the chucks 8' and 17 have been loosened, to uncouple the driving shaft from the drill rod, and permit the tubular drive shaft to slide back on the drill rod. As the hand wheel is turned in direction reverse to the feed motion, the nut 37 is caused to move to the right in the drawings, and the pressure plate, and the parts to which it is attached, are pulled by the traveling nut through the two tie bolts 42, 42, the screw of course turning, but not moving longitudinally, and the pressure plate slips over the threaded screw.

If an additional drill rod section is to be added to the drill rod, the water connection 4 is first removed from the rear end of the drill rod and then the section is added, after which the water connection is again attached at the rear end of the lengthened drill rod. All of the sections of the drill rod are rigidly joined to an adjoining section, and the drill rod is a rigid structure capable of being grasped by the chuck at any point throughout its length.

After the drill frame and its parts have been retracted, the chuck is again coupled to the drill rod, and the drilling operation is resumed, the feed being controlled by use of the hand wheel.

By means of an indicator or pointer 45 and a scale plate as 46, which is attached rigidly to the drill frame 11 as shown in Figures 1 and 7, the degree of compression or the tension imposed on the spring 40 may be ascertained by the operator of the drilling machine.

In many instances the expert operator of the drilling machine giving the required close attention to drilling operations, may ascertain by the "feel" of the hand wheel and the sound of the drilling, whether or not the drill is operating efficiently and properly, and his manipulation of the hand wheel is governed accordingly. However, a visual indicator may be employed to illustrate the relative positions of the nut 37 and the

pressure plate 29, and to indicate the normal compression of the spring when these parts are spaced properly; to indicate the sub-normal compression of the spring as when the nut and the pressure plate are too far apart, and the spring is expanded; and to indicate an abnormal compression of the spring when the pressure plate and the nut are too close together.

It will also be apparent that the initial compression of the spring to furnish the tension that holds the bit to its work, may be attained by turning the hand wheel to compress the spring against the resistance of the load of the drill frame and its supported parts.

While I have shown one exemplifying structure for the embodiment of my invention, it will be understood that changes and alterations are contemplated, and may be made, in the illustrated apparatus, within the scope of my claims, without departing from the principles of my invention.

Having thus fully described my invention, what I claim as new and desire to secure by Letters Patent is:

1. In a rotary drilling machine, the combination with a rotary drill rod, of a tubular drive shaft enclosing a portion of the drill rod, a drill frame and a supporting bearing on said frame for the shaft, a rotary power unit mounted on the frame for revolving said shaft, co-acting means on the power unit and shaft to retain the latter against longitudinal movement, and a detachable coupling between the drive shaft and the drill rod.

2. In a rotary drilling machine, the combination with a rotary drill rod, of an enclosing tubular drive shaft having a pair of spaced exterior shoulders, a drill frame, a power unit mounted on the drill frame, spaced bearings on said unit for said shaft co-acting with said shoulders to retain the shaft against longitudinal movement, a revolving element of the power unit fixed on the shaft between said shoulders, and a detachable coupling between the drive shaft and the drill rod.

3. In a rotary drilling machine, the combination with a rotary drill rod, of a tubular shaft enclosing a portion of the rod, a drill frame and a supporting bearing on the frame for the shaft, a motor mounted on the frame and enclosing the shaft, said motor having an element rotatable with the shaft, and a detachable coupling between the tubular drive shaft and the drill rod.

4. In a rotary drilling machine, the combination with a rotary drill rod, of a tubular shaft enclosing a portion of the rod, a detachable coupling between the drive shaft and the drill rod, friction rollers mounted in said coupling for engagement with the rod, means for causing said rollers to grasp the rod, and means for revolving the tubular shaft.

5. In a rotary drilling machine, the combination with a rotary drill rod, a tubular shaft enclosing a portion of the drill rod, a coupling between the drive shaft and the drill rod, friction rollers mounted in said coupling for engagement with the rod, means for causing said rollers to grasp the rod, a drill frame and a supporting bearing on the frame for the shaft, and a rotary power unit mounted on the shaft and frame for revolving the shaft.

WILLIAM J. MITCHELL.

CERTIFICATE OF CORRECTION.

Patent No. 2,019,761.

November 5, 1935.

WILLIAM J. MITCHELL.

It is hereby certified that the name of the assignee in the above numbered patent was erroneously described and specified as "Pneumatic Tool Company" whereas said name should have been described and specified as Chicago Pneumatic Tool Company, as shown by the record of assignments in this office; and that the said Letters Patent should be read with this correction therein that the same may conform to the record of the case in the Patent Office.

Signed and sealed this 7th day of January, A. D. 1936.

Leslie Frazer
